UNITED STATES PATENT OFFICE

2,458,702

ELEVATOR HATCHWAY DOOR OPERATOR

Randall Hains, Boonton, N. J., assignor to Elevator Supplies Company, Inc., Perth Amboy, N. J., a corporation of New Jersey

Application February 14, 1947, Serial No. 728,574

10 Claims. (Cl. 187—52)

1

This invention relates to mechanism carried by an elevator car for effecting opening and closing movement of the doors on the elevator, as well as the doors at the various shaftway openings served by the elevator.

This invention is employed in connection with door operating mechanism of the type which is mounted upon and carried by the elevator car. It includes means for effecting oscillation of a door operating lever which is connected to the elevator car doors and includes a clutch member operated thereby for cooperation with the shaftway doors to effect simultaneous movement thereof with the movement of the car door.

This type of mechanism is well known in the art and includes a clutch operated by and in conjunction with the car door operating mechanism for engaging a knob or roller on the shaftway doors when the car is stopped thereat for simultaneously opening and closing the shaftway doors. In such a mechanism the clutch comprises a pair of cooperating shoes, one of which is relatively fixed and the other relatively movable and normally arranged to be in open or started position when the car is moving in the hatchway. Each of the hatchway doors is provided with a knob or roller which passes between these shoes as the car moves vertically in the hatchway. When the car comes to a stop at any hatchway opening the shoes pass on opposite sides of the hatchway door roller which is positioned between them when the car comes to a stop. As soon as the car door operating mechanism begins to operate to open the car door or doors, the movable shoe of the clutch moves towards the relatively fixed shoe to engage the hatchway door roller between them. This clutch is mounted on the car doors so that as they are moved back the hatchway doors are moved simultaneously.

The specific object of this invention is to provide a new and improved form of quick-acting silent clutch mechanism of this type.

Other and more detailed objects of the invention will be apparent from the following description of the two embodiments thereof illustrated in the attached drawings.

This invention resides substantially in the combination, construction, arrangement and relative location of parts, all as will be described in detail below.

In the accompanying drawings:

Figure 1 is a view in elevation of an elevator car equipped with the mechanism of this invention in which car the car door is composed of one section, as illustrated;

2

Figure 2 is an enlarged detail front elevational view of the improved clutch mechanism of this invention showing the clutch closed;

Figure 3 is a similar view showing the clutch open;

Figure 4 is a lefthand elevational view of the mechanism showing some parts in section and some parts broken away;

Figure 5 is an enlarged detail perspective view with many parts removed showing the relatively fixed shoe and the pivoted levers for supporting the relatively movable shoe;

Figure 6 shows a simplified and modified construction with the parts in the position of the door closed and the clutch open;

Figure 7 shows this mechanism with the door partly open and the clutch closed;

Figure 8 is a similar view showing the door still further opened and the clutch still closed; and

Figure 9 is a similar view showing the door fully open with the clutch still closed.

As a background for this invention it may be stated that the subject matter thereof constitutes an improvement in the clutch mechanism disclosed in United States Patent No. 1,716,569, granted June 11, 1929, to Harold W. Shonnard. The car door operating mechanism including the power source and the linkage system is similar to that of the patent but the clutch mechanism disclosed in the patent has been modified in a manner which will be clearly set forth in the following description.

As illustrated in Figure 1, the mechanism is associated with an elevator car 1, which is adapted to travel in either direction in a hatchway. The loading and unloading opening in the front wall 3 of the car is normally closed by means of a door illustrated as comprising the section 2 which is supported on a track or rail 8 by means of hanger plates 4 and 5 in which are journaled the supporting rollers 6 and 7. A knob or roller for a hatchway door is indicated at 9, and as is well known, is attached to the shaftway side of the hatchway door. It will be understood, of course, that when all of the hatchway doors are closed their operating rollers 9 are vertically aligned so that the clutch on the car which is opened when the car door is closed can move vertically past them without contact.

The operating mechanism for the car door or doors is mounted on the elevator car and includes a motor 10 which drives a crank 15 through a gear train comprising the pinion 11, the intermediate gear 12, pinion 13 and driven gear 14 which operates the crank. The crank is provided

with a crank disc or roller 16 which cooperates with guides 17 and 18 mounted in a yoke 19 which is pivotally mounted at 22 on a fixed bracket or journal 23. The crank disc guides 17 and 18 are mounted in a slotted opening 20 in the yoke 19 and the lower portion of this yoke is provided with an arcuate slot 21 by means of which the upper end of the main operating arm 24 can be secured to the yoke at the desired angular position to provide the necessary adjustment to meet varying conditions likely to be encountered in elevator installations. As is well known, the lever 24 when in use is rigidly connected to the yoke 19 for rocking movement therewith on the pivot pin 22.

The lower end of the lever 24 is provided with an elbow or angularly shaped fitting 25 which is pivotally connected by means of the pivot pin 25^a to a lever 26 which is pivotally mounted on a supporting pin 27 secured to the clutch supporting plate 28. As is clear from Figure 1, the plate 28 is secured to the outer face of the car door 2.

Secured to the plate 28 by means of Allen screws 30 is an L-shaped bracket 29 on which is slidably mounted the relatively fixed clutch shoe 31. The shoe 31 is provided with a series of pins 32, of which the end pair as shown in Figure 2, are provided with a pair of lock nuts, and the central pair are plain guide pins. All of these pins are enclosed by coil springs 33 which lie between the shoe and the bracket to hold them in the position shown in Figure 2. Movement of the shoe 31 to the left is limited by the lock nuts. All of the pins 32 may slide in the holes in the bracket provided for them.

As is clear particularly from Figure 5, pivotally mounted on bearing pins 34 are a pair of levers 35 provided with pivot pins 36 to which the relatively movable shoe 38 is secured while allowing pivotal movement therebetween. The levers 35 provide for movement of the shoe 38 towards and away from the shoe 31 maintaining parallelism therewith. As is clear from Figure 2, the shoe 38 if free naturally tends to fall downwardly as the levers 35 move in a clockwise direction but to insure rapid and positive action coil springs 39 are provided which are anchored to aid this movement. The bracket 42 (see Fig. 2 for example) is secured to the plate 28 and adjustably mounted in it is a stop screw 43 having a resilient bumper member 44 positioned to engage the uppermost lever 35 to provide a silent stop therefor in an opening direction.

Secured to the underface of the shoe 38 is an adjustable cam 139. This cam is provided with three lock screws 40 operating in angularly arranged slots in the shoe 38 so that the cam can be tipped about the central lock screw to provide for final adjustment of this cam. The cam is provided with a sharply curved shoulder at its upper end and a curvilinear portion which is concentric with the pivot pin 27 about which the lever 26 rotates. Mounted on the pivot pin 25^a is a cam follower 41 which engages the periphery of the cam 139 and is preferably a ball bearing mounted roller.

When the car stops opposite a shaftway door the roller 9 thereof will be in the position shown in Figure 3, that is it will lie between the clutch shoes 31 and 38. At this time the clutch will be fully opened, which is the position shown in Figure 3. As the lever 24 starts in opening direction it will cause lever 26 to pivot in a counterclockwise direction around its supporting pivot pin 27. As a result the cam follower 41 will force

the cam 139 to the right as it rides up its sharply curved portion, moving the shoe 38 to the dotted position shown in Figure 3 when the highest point of the cam is reached. The relatively fixed shoe 31 is resiliently mounted, as is evident, to adapt for any irregularities in the position of the hatchway door rollers. These rollers are usually covered with some resilient material to reduce noise, and as the movable shoe 38 has a definite forward position when the clutch is closed, the ability of shoe 31 to be displaced as required prevents any undue binding or straining of the cooperating parts. As the sharply curved portion of the cam 139 is steeply inclined, only a little movement of the levers 24 and 26 is required to close the clutch so that the car door has but a slight opening movement before the hatchway door begins to open. The remaining movement of the mechanism does not affect the closed position of the clutch, that is it remains closed during the opening movement of the car and hatchway doors and remains closed during their closing movement until about the last inch of movement of these doors when the clutch begins to open. Thus both sets of doors move in unison. Actual attainment of this condition in practice is insured by reason of the adjustability of the cam 139 on the shoe 38. During the opening movement of the clutch the springs 33 speed the opening of the clutch, which opening is aided by gravity. In actual practice it has been found that these springs are not essential as the mechanism will operate usefully without them. The cushioning bumper 44 prevents overtravel of the clutch shoe 38 in an opening direction while contributing to silent operation of the mechanism.

Silent operation is further insured by the fact that the cam follower 41 is in contact with cam 139 for all positions of the mechanism.

The mechanism of Figures 6 and 9 inclusive is substantially like that previously described but involves a somewhat simplified mechanism in that the relatively fixed shoe 61 corresponding to the shoe 31 of the first form of the invention does not include any yielding construction. The shoe 61 is rigidly mounted on the supporting plate 60 corresponding to the plate 28. The relatively movable shoe 62 is supported upon a pair of pivoted arms 63 like the arms 35 and in this arrangement no springs are employed to aid the opening movement of the clutch. The cam 64 corresponds to the cam 139 and is adjustably secured to the underface of the shoe 62. The lever 24 with its fixtures 25 is pivotally connected as before at 25^a to the lever 26 which is pivotally mounted on the plate 60. In this form no cushioned stop corresponding to the members 42, 43 and 44 is shown, although it can be used.

The operation of this form of device is substantially like that of the other and the parts are in the various positions during the door opening cycle as progressively illustrated in Figures 6, 7, 8 and 9. In this form of the device, as in the previous form, the swing of the lever 24 is such that the cam follower 41 moves over the concentric portion of the cam 64 from its highest point to its lower end and partway back again, as is clear from Figure 9.

From the above description it will be apparent to those skilled in the art that the subject matter of this invention can be employed in other physical forms, and I do not, therefore, desire to be limited to the forms employed here for illustrating this subject matter, but rather only as required by the claims granted me.

What is claimed is:

1. A door clutch for an elevator system comprising a support, a pair of shoes, one of which is relatively fixed and the other of which is relatively movable on said support, means for pivotally supporting the latter for movement towards and away from the former while maintaining parallelism therewith, a cam attached to the latter, a lever pivotally mounted on said support for movement relative to said cam and having a cam follower on the free end thereof, and means for effecting oscillation of said lever whereby said relatively movable shoe is moved towards and away from said relatively fixed shoe.

2. In the combination of claim 1, said cam having a sharply curved portion and a less sharply curved portion.

3. In the combination of claim 1, said cam having a sharply curved portion and a less sharply curved portion, said second portion being substantially concentric with the pivot center of said lever.

4. In the combination of claim 1, said cam being adjustably secured to said relatively movable shoe.

5. In the combination of claim 1, said relatively fixed shoe including a resiliently supported working member.

6. In the combination of claim 1, said means for pivotally supporting the relatively movable

shoe comprising a pair of levers pivotally mounted.

5 7. In the combination of claim 1, said means for pivotally supporting the relatively movable shoe comprising a pair of levers pivotally mounted, and means for biasing their movement in one direction.

10 8. In the combination of claim 1, said means for pivotally supporting the relatively movable shoe comprising a pair of levers pivotally mounted, said relatively movable shoe being secured to said levers so as to tend to move towards open position under the action of gravity.

9. A clutch mechanism as described comprising a supporting plate having a shoe secured thereto, a second shoe pivotally supported on said plate for movement towards and away from the first shoe while maintaining parallelism therewith, a lever pivotally mounted on said plate having a cam follower on the free end thereof, and a cam secured to said second shoe so as to be engaged by said cam follower, operation of said lever causing movement of said movable shoe.

20 10. In the combination of claim 9, said cam having a sharply curved portion merging with a more flatly curved portion whereby initial movement of said lever causes full movement of the second shoe towards the first.

RANDALL HAINS.
